UNITED STATES PATENT OFFICE.

KYLE DERIAS OBENSHAIN, OF MCKINNEY, TEXAS.

OIL-BURNER.

1,375,062.

Specification of Letters Patent. Patented Apr. 19, 1921.

Application filed February 9, 1920. Serial No. 357,241.

To all whom it may concern:

Be it known that I, KYLE DERIAS OBENSHAIN, a citizen of the United States, and a resident of McKinney, in the county of Collin and State of Texas, have invented certain new and useful Improvements in Oil-Burners, of which the following is a specification.

My invention is an improvement in oil burners, and has for its object to provide an economical, and easily handled burner of the character specified, having a large capacity and wherein the burner is automatically controlled by the differential pressure 15 between the oil and steam within the burner head.

In the drawings:—

Figure 1 is a front view of the improved burner;

Fig. 2 is a longitudinal vertical section; Fig. 3 is a perspective view of the burner head;

Fig. 4 is a vertical section of the same;

Fig. 5 is a perspective view of the per- 25 forated ring;

Fig. 6 is a section on line 6—6 of Fig. 1; and

Fig. 7 is a side view with parts broken away, showing a modified construction.

In the present embodiment of the invention, the improved burner consists of a pipe or casing 1 having at one end a burner head to be described, and at the other end a T 2, with whose lateral branch there is connected a steam pipe 3.

The opposite end of the T 2 from the pipe 1, is partially closed by a cap 4, and an oil feed pipe 5 is arranged within the pipe 1 and in the T, the pipe 5 extending through 40 the cap 4 to a connection with one end of a T 6.

An oil feed pipe 7, from a suitable source of supply, is connected with the lateral branch of the T 6 and a short section of pipe 8 connects the other end of the T with a valve casing 9. A valve 10 is arranged within this casing for controlling the communication between the pipe 8 and the casing. The valve has a stem 11 which extends 50 through a stuffing box 12 at the outer end of the valve casing and is provided with a hand wheel 13 for convenience in manipulating the same.

An elbow 14 is connected with the casing 55 9, and extends laterally therefrom, and a

blow-out pipe 15 is connected with the elbow, the blow-out pipe extending approximately parallel with the pipe 1 toward the burner head, and to near the burner head as shown in Fig. 1.

It will be noticed, referring to Fig. 2, that one end of the casing 9 adjacent to the pipe 8 is conical to form a valve seat, and the conical valve 10 cooperates with this seat.

The burner head shown more particularly in Fig. 4 comprises a substantially cylindrical casing consisting of a lower section 16 and an upper section 17, which are detachably connected together by means of a tubular structure 18 extending axially of the casing, and integral at its lower end with the center of the bottom of the section 16, and abutting at its upper end the inner face of the top of the section 17, the two sections 16 and 17 being cup-shaped, as shown. The section 17 has a central opening in its top, and the upper end of the tubular section 18 is interiorly threaded to receive a screw plug 19, which secures the sections together, the plug engaging the tubular structure 18.

The pipe 1 communicates with the section 16 by means of a nipple 20 near its bottom, and the section 5 communicates with the tubular structure by means of an interiorly threaded opening 21 into which the pipe 5 is threaded, and it will be noticed that the pipe 5 is spaced apart from the wall of the pipe 1 to provide an annular passage between the said pipes. The abutting edges of the sections 16 and 17 are rabbeted, as shown, the former section to receive a ring 22, and the latter to receive a washer 23. The tubular structure 18 is exteriorly reduced to form an annular shoulder on which the washer 23 rests, and the washer is spaced above the ring, as clearly shown in Fig. 4.

The internal diameter of the ring 22 is greater than that of the tubular structure so that there is provided a relatively large annular opening between the tubular structure and the inner edge of the ring. The section 17 of the casing is cut away at the edge that abuts the section 16, at the opposite side from the entrance point of the pipes 1 and 5, to form an arc-shaped outlet 24 for the burning gases. This outlet as indicated in Fig. 3 is approximately 120° in length, and it will be noticed referring to Figs. 4 and 5 that the washer 23 has an arc-shaped series of openings 25 on its inner 110

edge and at the slot or passage 24. This washer 23 also has a notch 26 in its peripheral edge which is adapted to engage a stop in the rabbet of the section 17 to prevent angular movement of the washer with respect to the section.

The operation of the device is as follows:

To start the improved burner, the burner being duly installed and ready for service, 10 steam is first admitted to the burner, the steam passing through the pipe 1 into the chamber 27 below the washer 23, and this steam escapes through the slot or passage 24. A piece of burning waste is held in the furnace and near the nozzle and the oil under suitable pressure is admitted to the burner by way of the pipe 5, passing into the tubular structure 18 and out through radial openings 28 into the chamber 29 15 which is above the washer 23. This oil passes down through the openings 25 mixes with the steam and is ignited by the burning waste.

It will be noted that the steam and oil pressure oppose each other in the burner head and because of this fact the burner is practically self-regulating in its operation. Any rise in boiler pressure reacts through the burner on the oil supply and retards 25 it while a drop in boiler pressure increases the flow, thereby the tendency of the burner, all things being equal, is to maintain a uniform boiler pressure even with a variation in load. The burner may be easily cleaned of 30 sediment deposited by the oil during use by cutting off the oil, it being understood that suitable cut-offs are provided in the pipes, opening the valve 9 and permitting the steam to blow back through the casing 9 and the pipe 15. The oil and the atomizing 35 agent, steam in the present instance do not mix until they pass from the chambers 27 and 29. The chamber 29 acts as a sort of reservoir for the oil, and is kept full of oil. 40 This oil is heated to a high degree by the in-rushing steam in the chamber 27, and the oil passes through the washer 23 in a very expansive condition, contacting with the outgoing steam, just within the slot or 45 passage 24.

It will be noticed, referring to Fig. 4 that the openings 25 are above the imperforate portion of the ring 22.

The size of the openings 25 greatly influences the combustion. When the openings 55 are large and few in number, the combustion is violent in character and explosive, vibrating furnace walls and other structures in the vicinity. On the other hand when 60 small openings are used the combustion is comparatively quiet and vibration is reduced to a minimum. Hence, a large number of small openings is provided which insures not only perfect combustion but a 65 broad fan-shaped flame from the burner

that burns quietly and does not jar the furnace walls.

In operation the oil supply valve is always wide open, while the steam valve is open sufficiently to hold the oil in check 70 and maintain proper combustion.

In the embodiment of the invention shown in Fig. 7, the fuel feed pipe 30 is arranged within the steam pipe 31, and the burner head indicated at 32, is on the fuel feed 75 or oil pipe. This head, as shown, is a closed casing having an arc-shaped series of openings 23 through which the oil is delivered, the steam being delivered through the pipe 31. With this arrangement the steam pipe 80 is open, the space between the pipes forming an annular chamber for the steam and the outlet for the steam is reduced by the head so that there is some choking or increase of pressure at this point. Hence, 85 the regulation of the feed will be in the same manner as in the construction shown in Fig. 1. An increase of boiler pressure will decrease the fuel feed. With this arrangement, the same arrangement of valves and 90 piping is used as shown in Fig. 1, the burner head 32 taking the place of the head 16-17.

I claim:

1. A burner head comprising a substantially cylindrical casing consisting of upper and lower abutting sections, the lower section having a tubular member extending axially thereof and abutting the outer end of the upper section, said upper section 95 having an opening registering with the bore of the tubular member, a plug passing through the opening and having threaded engagement with the tubular member, said tubular member having a lateral nipple for 100 connection with a fuel supply pipe and having lateral openings near its top for permitting the fuel to flow into the casing, a partition extending transversely of the 105 casing between the sections and between the last named openings and the nipple, the casing having a lateral port and the partition having openings at the port, said casing having a ledge below the said openings on to which the openings feed, and means 110 for supplying air to the lower section of the casing.

2. A burner head comprising a substantially cylindrical casing, having an axial tubular member, said tubular member having a lateral nipple for connection with a fuel supply pipe and having lateral openings near its top for permitting the fuel to flow into the casing, a partition extending transversely of the casing between the sections 120 and between the last named openings and the nipple, the casing having a lateral port and the partition having openings at the port, said casing having a ledge below the 125 said openings onto which the openings feed,

and means for supplying air to the lower section of the casing.

3. A burner head comprising a substantially cylindrical casing having a transverse partition intermediate its ends, and having a feed opening below the partition, the partition having openings at the feed

opening of the casing, the casing having a ledge below the said openings onto which the openings feed, means for supplying liquid fuel to the casing above the partition, and means for supplying air under pressure to the casing below the partition.

KYLE DERIAS OBENSHAIN.
